UNITED STATES PATENT OFFICE.

ISRAEL W. MARSHALL, OF YORKLYN, DELAWARE, ASSIGNOR OF ONE-HALF TO THOMAS E. MARSHALL, OF YORKLYN, DELAWARE.

PROCESS FOR MANUFACTURING INDURATED FIBER.

No. 897,758.

Specification of Letters Patent.

Patented Sept. 1, 1908.

Application filed October 8, 1907. Serial No. 396,404.

To all whom it may concern:

Be it known that I, ISRAEL W. MARSHALL, a citizen of the United States, residing at Yorklyn, in the county of Newcastle and 5 State of Delaware, have invented certain new and useful Improvements in Processes for Manufacturing Indurated Fiber, of which the following is a specification.

This invention relates to improvements in 10 processes for the manufacture of indurated or vulcanized fiber, and has for its objects: First, in methods or processes whereby such material may be produced in sheets equal in width to the capacity of the machine, and of 15 a length limited only by the supply of material. Second, in processes whereby the manufacture of such material may continue uninterruptedly, for an indefinite period, and in which the product is thoroughly 20 homogeneous and of like density in all parts of the sheet. Third, in processes whereby all waste of material used in coalescing and combining the several sheets comprising its ultimate thickness, is prevented, the same 25 being conserved for further use.

With these objects in view my invention consists in peculiar processes and uses of certain means and mechanisms illustrated in the annexed drawings, forming part of these 30 specifications, and in which have been used similar characters of reference on all similar parts throughout the several views.

Figure 1, is a diagrammatic view showing the course taken by the sheets, constituting 35 the fiber from the rolls, past the combining cylinders. Fig. 2, is a continuation of the same, indicating the passage taken in cooling and washing. Fig. 3, is a further continuation through the final washing and 40 heating rolls. Fig. 4, shows in a similar manner its passage through the calendering rolls to the complete product ready for removal. Fig. 5, is a plan view of the washing tank and piping system. Fig. 6, is a side 45 elevation of the same, including the pumping arrangements. Fig. 7, is a plan view of the drive. Fig. 8, is a continuation of the same. Fig. 9, is a side elevation of a single train 50 unit of the driving means. Fig. 10, is a duplicate view but showing the chain disengaged. Fig. 11, is a plan view of the same. Fig. 12, is a partial side elevation and section of a portion of one tank, and its superstructure. Fig. 13, is a transverse vertical sec-

tion of the same. Fig. 14, is a side elevation 55 of the submerging roll controlling means. Fig. 15, is a front elevation of a pair of the roll controlling means. Fig. 16, is a side elevation of the sheet immersing or combining machine. Fig. 17, is a detail of the immersing means, and, Fig. 18, is a detail of the 60 scraper.

It is necessary in my process to treat the sheets of paper with a chemical solution acting on the vegetable matter of which they 65 are comprised, to partially gelatinize or albumenize the fibers that they may coalesce and adhere under subsequent operations and become indissolubly united into a single sheet of fiber; this is accomplished as follows:

As many of the rolls of paper as are needed to make the finished fiber of desired thickness are placed on the combining machine shown in Fig. 16, the rolls being supported 75 on suitable shafts resting in open bearings 1, formed on the frame 2 of the machine and so arranged that each sheet may be unrolled without interfering with the others. These sheets all pass under the common roll 3, over 80 the separating rolls 4, removably mounted in the stand 5, to the submerging rolls 6 and 7, respectively, each pair being so arranged as to keep the sheets out of contact with each other or from any part of tank 8, in which 85 they are located; these rolls are suspended from levers 9 and 10, in such manner that they may be raised entirely free from and above the tank 8, by drawing down the lever 9; both levers being fulcrumed on top of the 90 tank as at 11 and 12, and operated by the chain 13, the same being wound on the shaft 14, provided with a suitable ratchet device 15, and hand wheel 16. This arrangement provides for the ready disposal or removal of 95 the paper sheets on the submerging rolls without disturbing the contents of the tank 8, which is filled partially with a solution of zinc chlorid, kept at a strength, as indicated by a hydrometer, of 70 and 71 Baumé, and 100 at a temperature of between 70° and 75° Fahrenheit.

The action of the zinc solution is to partially gelatinize or albumenize the vegetable fibers, causing them to coalesce and adhere 105 according to the more or less perfect saturation given them.

Excess liquor is removed from the several

combined sheets as they pass over the edges of the square scrapers 17 and 18, set in the standard 19, over the tank 8, and applied respectively to the lower and upper side of the sheet, on its passage to the drying and combining cylinders 20 and 21; the latter and larger cylinder is set in fixed bearings 22, on the frame of the machine, at the front end, and is supplied with steam to maintain a 10 temperature of approximately 90 degrees.

The upper cylinder 20, is maintained in bearings 22, movable on the frame portion 23, and is provided with a chain 24, which may be wound on the shaft 25, through the 15 action of the gear 26, worm 27, shaft 28 and hand-wheel 29, as indicated, the purpose being to provide means for elevating the cylinder 20, at such times as may be desirable, as in the insertion of a new sheet.

20 Normally the cylinder 20, rests its weight on the fiber disposed between it and the lower cylinder 21; it is also provided with means for steam entrance—not shown—and the temperature is maintained at about 180 25 degrees, or twice that of the lower cylinder; the heat and pressure resulting in effectually combining the several previously treated sheets into a single sheet of fiber. From these cylinders the sheet passes over an extended series of rollers, allowing the air to 30 have full access on both sides, in a manner curing, cooling and drying the same during the exposure, which is of from eight to ten minutes duration, its travel being at the rate 35 of eight to twenty feet per minute, according to the thickness of the fiber, while the length of its course approximates 100 feet. The foregoing aeration is of the utmost importance as without it the product is practically 40 worthless. The fiber sheet is then introduced into a series of separate tanks A, B, C, and D, in the first of which much of the zinc 45 solution is retained, some in the second, less in the third and scarcely a trace in the fourth and last; the approximate percentage being respectively 15%, 7%, 2% and 0%. These 50 tanks are so connected by piping that the contents of any one can be removed and the tank refilled from any other tank or with 55 fresh water. The usual procedure being at the beginning of each day's run to empty tank A, through the pipe 40, into the vat 41, below the floor,—through gravity—by opening the valve 42, and having the valves 43, 55 44 and 45 closed; thereupon opening valves 46 and 51, having valves 47, 48 and 49, closed as must also be valves 50, 52 and 53, then starting the pump 55, resulting in transferring the contents of tank B, to tank A, and 60 proceeding in a similar manner with the others, finally filling tank D, with fresh water. Thus all the sedimentation and chlorinated zinc are removed to the first tank to receive the freshly treated fiber, the strong so-

lution being emptied into the vat 41, eventually taken from thence by the pump 56, and discharged through the pipe 57, to a lead lined condensing vat—not shown—where the solution is condensed by evaporation to the proper degree, (66 to 67, Baumé, 70 when hot), ready for use again and allowing of little or no waste of material, the zinc solution being entirely reclaimed. From these tanks the sheet is conducted between a pair of squeezing rollers to remove excess liquid 75 and through a supplementary soaking bath, kept supplied with clear water, and in which the fiber may be retained indefinitely, thus removing the last traces of the chemical, after which it passes through the usual heated 80 drying and curing cylinders to calendering rolls and from thence may be cut into separate sheets or rolled as desired. These latter operations are common in the manufacture of paper and need not be related. 85

The peculiarities noticeable are, the necessity for exposure to the air before washing, without which the sheets are liable to disintegrate and do not possess a desirable degree of cohesion; the absolute and complete removal of all traces of the zinc solution, lack of which leads to an imperfect product, unsuitable particularly for electrical purposes. The enormous shrinkage that takes place, which amounts to over ten 95 per cent. in width and even a greater percentage in thickness.

The method of obtaining the exposure has been described, as has the means used in supplying the washing tanks with water; it now 100 remains to consider the means for submerging the sheet in the bath tanks A, B, C, and D, over which the sheet travels in its aeration. On its return passage the sheet is turned again over the tank A, and allowed 105 to rest on the rolls 60, held in bearings 61, attached to the top of the tanks on its side edges. When the front end of the sheet has reached the extreme end of the tank, the roll 62, is lowered by means of the vertical shaft 110 63, normally contained in the fixed tube 64, attached to a suitable support as indicated in Figs. 12, 13; 14, and 15; the lower ends of the several tubes 64, are interconnected by suitable brace members 65 and 66, attached 115 to the sockets 67, which have bearings for the shaft 68, transversely of the tank and on which are mounted spur gears 69, adapted to engage with the rack teeth, cut in the side of the vertically sliding shaft 63, the same 120 being provided with bearings 63', for the ends of the roll 62.

A handle 70, is provided with which to operate the transverse shaft 68, and transmit motion uniformly to the roll through the 125 pair of vertical shafts to which it is connected. This handle is preferably operated in such manner as to cause the roll 62, to de-

scend just sufficiently fast to take up the slack in the on-coming sheet of fiber, keeping it reasonably taut until the roll has reached the end of its downward travel, whereupon 5 the handle is transferred to the next transverse shaft and the second roll lowered in a similar manner, thus the tank A, will be filled to its capacity before any of the fiber enters the succeeding tanks and hence most of the 10 adhering solution of zinc chlorid removed and retained in the tank A.

Figs. 7 and 8, indicate the driving means as applied to the entire construction, the wheel 80, being adapted to receive the driving 15 belt from the engine or other prime motor used; this wheel is secured on the shaft 81, having the bevel gear 82, and beyond the bearings—indicated conventionally—a sprocket wheel 83, on which is a link belt 20 84, running over an idle wheel 85; between these are located the driven wheel 86, communicating motions to the last of the series 25 of stationary rolls 60, on the tank A. The distance between the centers of the wheels 83 and 85, and the slackness of the driving chain is such that it is easily possible to raise the chain out of engagement with the cogs on the driven wheel 86, letting it run free alongside of it, thereby stopping the rolls on 30 the tank from rotating completely but without interfering with the drive on the succeeding tank rolls and to which power is communicated by the idle wheel 85, which is idle only so far as tank A, is concerned, acting as 35 an intermediate for the following tank rolls. This effect can be realized from an inspection of Figs. 9, 10 and 11, which show clearly another result attained by the use of a comparatively long and slack chain belt, *i. e.*, 40 that of the chain riding up and over the cogs in the driven wheel, at such time as it ceases to rotate for any cause, thus preventing tearing asunder the wet fiber or doing other injury to it or the mechanism. Use is also made of 45 the same driving method in all the following tank roll devices as indicated.

Engaging with the bevel gear 82, is a similar gear 87, on the shaft 88, carrying the coned friction roll 89, working in connection 50 with its mate 90, secured on the main shaft 91, in such manner that the relative speed may be increased or diminished at will. Other speed changing cones of similar nature are used at the combining machine, the drying 55 rolls and calendering rolls, between the main shaft and the transverse counter, or driving shafts, as required, as obviously the relative speed of each machine or roll must be timed with absolute accuracy to compensate 60 for the shrinkage of the product as it occurs or damage results.

In the manufacture of indurated fiber of over a certain thickness, I may prefer to change the exact methods of operation, as

hereinbefore described and which are particularly applicable to comparatively thin sheets traveling continuously from the paper rolls to the finished product. These changes consist merely in the more extended use of the soaking tank wherein the sheets may remain an indefinite length of time, depending on their thickness, the object being to remove every possible trace of the chemical used in coalescing the sheets, except such as has become synthetically incorporated in the fiber, and I may prefer to use such soaking baths altogether in place of the tanks herein noted.

Having thus described my process, what I claim as new and desire to secure by Letters Patent is:

1. The process of making indurated fiber, consisting of subjecting a plurality of vegetable paper sheets to the action of a chemical whereby they are partially gelatinized, uniting the sheets under the combined influence of heat and pressure, cooling, aerating and subsequently washing until all traces of the chemical are removed and finally passing through drying rolls and calender rolls, all substantially as shown and described.

2. The process of making indurated fiber, consisting of subjecting a plurality of vegetable fiber sheets to a bath containing a solution having the property of causing a chemical change to take place in said vegetable fiber whereby a union of the sheets may be effected, substantially uniting said sheets by heat under moderate pressure, cooling and air curing, followed by repeated washing and soaking until no trace of the chemical used can be detected and the final passage of the united fiber sheet through drying rolls and calender rolls, all substantially as shown and described.

3. The process of continuously making indurated fiber, consisting of combining a plurality of sheets made of vegetable matter and having a relatively soft, porous texture, by saturating them each independently with zinc chlorid, removing the excess, immediately pressing the sheets in intimate contact between heated cylinders, the upper of which is maintained at twice the temperature of the lower, circulating the sheet in the air until cool, passing through a series of water baths, until all traces of the zinc chlorid have disappeared, and finishing the fiber sheet in drying rolls and calender rolls, all substantially as specified.

4. The process of making indurated fiber or the like, consisting in treating a plurality of separate paper sheets to the action of a solution having the property of causing a chemical change in the said sheets whereby they may become integrally incorporated into a single sheet, immediately subjecting the sheet to moderate pressure between

heated cylinders, exposing the sheet in the air until cool and practically dry, washing and soaking the sheet in a water bath, an indefinite period of time, dependent upon its thickness, until the chemical solution has been removed except that which has become synthetically incorporated in the sheet, and finishing the said sheet as usual.

In testimony whereof I have signed my name to this specification, in the presence of 10 two subscribing witnesses.
